UNITED STATES PATENT OFFICE

ALFRED E. OWERS, OF BROOKLYN, NEW YORK.

SHOE.

1,043,350.

Specification of Letters Patent.

Patented Nov. 5, 1912.

Application filed June 11, 1911. Serial No. 638,627.

To all whom it may concern:

Be it known that I, ALFRED E. OWERS, a citizen of the United States, and a resident of Brooklyn, New York, have invented new and useful Improvements in Shoes, of which the following is a specification.

My invention relates to shoes and it has for its object the production of a shoe having a plurality of uppers, the shoe being so constructed that one or more of the said uppers may be removed easily and the parts so secured that none of the uppers will be injured and so that there will be no appreciable evidence of the securing means after the removal of any of the uppers. The uppers may be removed one by one as they are worn or soiled or when it is desired to change the appearance of the shoe.

In the shoe commonly known in the art, when the upper is worn or soiled the shoe is thrown away. Where the uppers of shoes and slippers are made of a soft or glossy texture or are made of silk or satin or other fabric, they soon become soiled or injured beyond repair and the shoe or slipper becomes worthless merely because of its soiled appearance, while the sole and the linings may be perfectly good in every way. In order to save this loss I have invented a shoe which has two or more uppers, each independently secured and each easily removable from the others and presenting in each case a perfect unimpaired upper.

The invention may be embodied in many different constructions and many different arrangements may be used in connecting the parts together. Such features may be greatly modified by those skilled in the art without departing from the spirit of the invention and the shoe or slipper produced will still contain the invention.

In the drawings I have illustrated one or two constructions embodying the invention to show that it is practical and operative.

In Figure 1 is shown a slipper involving in its construction the use of the invention having a part of one of the uppers removed. Figs. 2, 3 and 4 show in a conventional way the manner in which the parts of the slipper are secured together. Fig. 5 shows the arrangement of parts after one of the uppers has been removed. Figs. 6 and 7 show a modified construction and Figs. 8 and 9 show further modifications of the slipper.

Referring to Figs. 1 to 5, 1 is the sole, 2 is the heel, 3 and 4 are the uppers. In the

slipper illustrated the upper 4 is made of leather, and its parts are assembled in the manner well known in the art. The parts are stitched along the upper edge 5 and at the back 6. The upper 4 is also secured to the sole 1. The upper 3 is also sewed along the back at 7 and then secured to the shoe. The method of securing the upper 3 may be varied according to the results desired or the advantages to be gained and, particularly, according to the material used. I have illustrated and shall describe the more efficient and advantageous methods usable in connection with the manufacture of the multiple upper slippers. This however as stated before may be greatly varied and the illustrations and the descriptions thereof may, and will undoubtedly, suggest other methods which involve the use of my invention.

In the arrangement of the parts shown in Figs. 2, 3 and 4, the French binding 8 is secured to the upper 4 in the manner well known by the stitches 9. The upper 3 is then secured to the upper 4 by means of the stitches 10. The stitches 10 may be lock stitches if desired but if a loop stitch is used the upper 3 may be easily removed by starting the stitches whereupon the thread may be easily pulled out and the upper will fall from the slipper. The thread 10 is sewed through the French binding. It may be sewed along the same line that the stitches 9 are sewed. For convenience and clearness of illustration the stitches 9 and 10 and the stitches hereinafter referred to are shown separated from each other by a short distance. They, however, may be located in the same lines or in close parallel lines to avoid the mutilation of the parts and preserve to the inner uppers the same presentable appearance that each would have in the ordinary shoe.

After the upper 3 is secured by the thread 10 it is turned up and the lining 11 is sewed to the upper 4 by means of the lock stitch 12, sewing along the French binding 8 and just beneath the fold 13 so as to cause the lining to draw tightly over the fold. The upper 3 is then drawn over the French binding so as to make a neat, smooth edge and is then secured preferably by a loop stitch 14 as shown in Fig. 4. A third upper may be secured in substantially the same way, that is, by sewing its folded edge with a loop stitch to the edge of the upper 4 and along the folded edge of

the upper 3, and then after the lining is sewed on, drawing first the upper 3 over the French binding and sewing it with a loop stitch and then drawing the third upper 5 over in the same way and sewing it with a loop stitch. The uppers are lasted independently, the upper 4 being secured first and then the upper 3. They are then sewed together to the sole 1 by the stitches 16.

10 In Fig. 5 is shown the arrangement of parts when the upper 3 is removed. The slipper may be first worn, the shoe presenting the appearance given by the upper 3, and when it is soiled the upper 3 may be 15 removed by pulling out stitches 10 and 14 and cutting close to the stitches 16, whereupon the upper 4 will give the appearance of newness, both in style and freshness of appearance.

20 In Figs. 6 and 7 I have shown an upper having its edge protected by a binding. The upper 4 is provided with a French binding as heretofore described. The upper 3 may then be sewed to the upper 4 by 25 the loop stitch 19 and the American binding 18 may be placed over the edge of the upper 3 and the French binding and secured by the loop stitches 20. The upper 3 may be removed by merely cutting or pulling out 30 the stitches 19 and 20 and cutting it close to the stitches 16.

In Fig. 8 is shown a modification wherein the edge of the upper 3 is turned over the French binding and secured by the loop 35 stitch 21. If desired the edge 22 may be trimmed just beneath the line of stitches after the upper has been sewed on.

In Fig. 9 is shown in a conventional way the arrangement of the parts of a slipper 40 which has three uppers. The slipper shown in Fig. 9 is like that shown in Fig. 8 except that a plurality of outer uppers are secured to the inner upper. In the figure, the second outer upper 28 is secured to the uppers 45 3 and 4 by means of the stitches 29. The stitches 29 are located along lines substantially the same as those in which stitches 12 and 21 are located in, although in the figure, for clearness of illustration, stitches 29 50 are indicated a little above the other stitches.

In each case above described additional uppers may be secured to the slipper substantially in the same manner that the upper 3 is secured, and in that way a multiple 55 upper slipper or shoe may be made. The methods used may be greatly varied and different methods may be combined in the manufacture of a single slipper. Also in each case the uppers may be lasted independently.

In the preferred form of construction the

upper 4 is made of leather and is first lasted so that when it is sewed to the upper 3 and the sole it will receive all the strain ordinarily brought to bear in the use of a shoe. 65

What I claim as new and desire to secure by Letters Patent is the following combinations of elements:—

1. In a slipper the combination with a sole and an upper having a lining, of an 70 outer upper secured to said inner upper along the upper edges of the inner upper and the outer upper and to the said sole.

2. In a slipper, the combination with a 75 sole and an upper of leather having a lining, said upper having a binding located along the upper edge thereof, of an upper of fabric completely covering said leather upper and secured to said sole and to said leather upper along said binding. 80

3. In a shoe, the combination with a sole, of an upper, said upper having a lining, said upper and lining having their ends sewed together to form the back seam of the shoe, and a second upper, said second 85 upper having its ends sewed together to form a second back seam independent of the first back seam, said uppers being secured to said sole and to each other along their upper edges. 90

4. In a slipper the combination of a lining, a sole and an upper secured to the said sole, a binding for covering the upper edge of the said upper, a second upper secured to the said sole and a second binding for 95 covering the upper edges of the said uppers.

5. In a slipper the combination of a plurality of perfect uppers, each of the outer of said uppers completely covering the inner of the said uppers, said uppers being secured 100 together along their upper edges, each outer upper being sewed to the inner upper along the upper edge of the inner upper, the lines of stitching uniting all the outer uppers to said inner upper being substantially coincident.

6. In a slipper the combination of a sole and a plurality of perfect uppers located one within the other, a lining located within the inner upper and a binding for covering 110 the upper edge of the inner upper the other of the said uppers being connected to the inner of the said uppers along the said binding and the said uppers being connected to the said sole. 115

In testimony whereof, I have signed my name to this specification, in the presence of two subscribing witnesses.

ALFRED E. OWERS.
